DESIGN FOR A GLASS DISH.

No. 38,615.

Specification for Design.

Patented June 11, 1907.

Application filed May 16, 1907. Serial No. 374,108. Term of patent 7 years.

To all whom it may concern:

Be it known that I, HERMAN RICHMAN, a citizen of the United States, residing at New York, in the borough of Richmond and State of New York, have invented a new, original, and ornamental Design for a Glass Dish, of which the following is a specification, reference being had to the accompanying drawing, forming part hereof.

In the drawings: Figure 1 is an elevation

of one half of the dish the other half which is identical with that shown being cut away, and Fig. 2 is a side view of the same.

I claim:

The ornamental design for glass dish, as shown.

HERMAN RICHMAN.
